United States Patent Office

Des. 196,991
Patented Nov. 26, 1963

196,991

REFRIGERATION COMPRESSOR

Pierre Henry Gallay, 11 bis Rue Jean Mermoz,
Paris, France

Filed Apr. 17, 1961, Ser. No. 64,770

Claims priority, application France Nov. 15, 1960

Term of patent 14 years

(Cl. D65—1)

Fig. 1.

Fig. 3.

Fig. 2.

Fig. 4.

FIG. 1 is a front elevational view of a refrigeration compressor showing my new design;

FIG. 2 is a top plan view thereof;

FIG. 3 is an elevational view taken from the right side of FIG. 1 thereof; and

FIG. 4 is an elevational view taken from the left side of FIG. 1 thereof.

The dominant features of my design reside in the portions shown in full lines, which portions are characterized by the configuration of the top portion thereof.

I claim:

The ornamental design for a refrigeration compressor, as shown and described.
